UNITED STATES PATENT OFFICE.

HENRY CROWE, OF SALTBURN, ENGLAND.

OPERATING-GEAR FOR HYDRAULIC VALVES.

1,313,523.

Specification of Letters Patent.

Patented Aug. 19, 1919.

Application filed June 24, 1918. Serial No. 241,598.

To all whom it may concern:

Be it known that I, HENRY Crowe, a subject of the King of England, residing at Saltburn-by-the-Sea, in the county of York, 5 England, have invented new and useful Improvements in Operating-Gears for Hydraulic Valves, of which the following is a specification.

This invention has reference to hydraulic valves of the type described in my specification, Serial Number 199,957 filed Nov. 2, 10 1917, and adapted to control single and double acting cylinders; the improvements consisting chiefly of the particular arrangement and method of gear operating the valves. The valve consists in the case of a single acting valve of one inlet and one exhaust miter valve, and in the case of a double acting valve of two inlet and two 15 outlet or exhaust miter valves, all placed on one center line.

In order that the invention may be clearly understood, I refer to the drawings in which:

Figure 1 is a sectional elevation taken through one of the similarly constructed inlet or exhaust valves, in combination with the operating gear therefor;

Fig. 2 is a side elevation of a cam or 20 weigh bar I employ to operate the valves; and

Figs. 3 and 4 show different views respectively of the arrangement of coupling the valves of a double acting valve with each other and to a double acting hydraulic cylinder.

Figs. 5 and 6 represent views to show the connection of the valves of a single acting valve and its coupling to a single acting 25 hydraulic cylinder.

Similar parts are designated by like references throughout the several views.

The construction of the inlet and exhaust valves forming the group valve is of substantially known design, Fig. 1, and is not intended to form part of the invention. The arrangement, however, of the valves is important and is as follows.

In the case of a double acting valve there 30 are two inlet valves a^1 a^2 and two outlet or exhaust miter valves a^3 a^4 , all placed on one center line, Figs. 3 and 4; the underside of the inlet valve a^1 being connected by a passage a^{13} to the topside of the exhaust valve a^3 . Similarly the underside of the inlet 35 valve a^2 is connected to the topside of the

exhaust valve a^4 by the passage a^{24} . L is the inlet branch of the double acting valve and connected to the hydraulic supply main (not shown), while M designates the connection from the underside of valve a^1 and the upper side of valve a^3 to one end of the double acting hydraulic cylinder O which latter is of the usual construction. N is the connection from the underside of the inlet valve a^2 and the upper side of the exhaust valve a^4 to the other end of the said hydraulic cylinder O, and P is the exhaust or outlet connection to the underside of both exhaust or outlet valves a^3 , a^4 .

In the case of a single acting valve the latter is coupled to a single acting hydraulic cylinder, Figs. 5 and 6, a^1 being the inlet valve and a^3 the outlet or exhaust valve, while L designates the connection to the hydraulic pressure supply main, leading to the upper side of the inlet valve a^1 . A passage Q connects the underside of said inlet valve a^1 with the upper side of the exhaust valve a^3 and connected to and communicating with the passage Q is the branch R which in turn forms a connection with the single acting cylinder S. P is the exhaust branch or outlet connected to the underside of the exhaust valve a^3 , Fig. 5.

The gear for operating these valves consists of a cam shaft or weigh bar f, illustrated more clearly in Figs. 1 and 2; placed at a distance away from the center line of the valves, the center line and pivot of rotation being designated by X and Y respectively. Levers g are furthermore provided, one for each valve and placed at right angles to the weigh bar f, each of which levers is adapted to lift its own particular valve when the weigh bar is being rocked. The weigh bar or cam shaft f is formed with three cam surfaces f^1 , f^2 , f^3 which are so arranged that they give great leverage and slow motion which is required when just opening the valves against heavy hydraulic pressures, thus dispensing with the necessity for pilot valves in a great many cases, and when once the valve is lifted off its seat, the form of the cam shaft or weigh bar gives the valves quicker and high lift with less leverage. As will be seen from the sectional view in Fig. 1, the faces f^1 , f^2 are the ones which actuate the levers g. The face f^1 , horizontally disposed and situated nearest the center of rotation Y, effects the gradual opening of the valve and acting as it does

at a comparatively short leverage, is much more powerful than the lift subsequently effected by the face f^2 which comes into operation when the extreme left hand corner is 5 raised above the horizontal, the leverage in which case is considerably extended. But at this stage the resistance to the opening offered by the valve is of course much less than at the initial stage, the result being 10 that the lever g is lifted by the face f^2 more rapidly though with less power than is the case when the face f^1 is in operation. The right hand side cam face f^3 is cut away to provide clearance for the lever g when the 15 cam or weigh bar is rocked in the opposite direction to that just described.

From Figs. 1 and 2 it will be noted that the said cam faces are so arranged that when the inlet valve a^1 is open, its companion exhaust valve a^3 is closed; at the same time the exhaust valve a^4 is open while its companion inlet valve a^2 is closed. When the weigh bar f is moved over in the other direction the action of these various valves is 20 of course reversed. It will be understood that the weigh bar or cam shaft is adapted to be oscillated by means of a lever or the like inserted in one of the holes f^4 , in the ends of same. The extent of the movement 25 of the weigh bar is limited by stops in the form of extensions h , h^1 of the bedplate B of the valve.

The ends of the levers g , opposite the weigh bar f , are carried on adjustable supports h , the object being to readily adjust the clearance i , between the valve spindle b^1 and a spindle j operating or acting on said valve spindle and resting on the lever g .

By this method of operating the valves, 40 each lever g operates its own particular valve, so that in the case of a double acting valve there are four levers, Figs. 3 and 4, while in the case of a single acting valve there are two levers only, Figs. 5 and 6. 45 The cam shaft or weigh bar f , in the latter case, is accordingly provided with correspondingly disposed sets of cam surfaces f^1 , f^2 , f^3 .

Moreover, the arrangement described and 50 shown with reference to Figs. 3 and 4, allows of the adjustment of one or both exhaust valves so as to be slightly open at the same time and thus the hydraulic machinery which is controlled by this group valve is 55 prevented from creeping, which it would do in the case of the ordinary method of con-

struction where all the four valves are down on their respective seats.

This creeping takes place when an inlet valve slightly leaks and the exhaust valve is 60 comparatively tight. In practice this creeping often exists and it is entirely prevented in the present arrangement.

Having now fully described my said invention what I claim and desire to secure 65 by Letters Patent is:—

1. In the herein described operating gear for hydraulic valves controlling a double acting hydraulic cylinder, the combination, with the said hydraulic valve consisting of 70 two inlet and two exhaust miter valves all placed on one center line, of a weigh bar placed at a distance from the center line of the valves and having differential cam surfaces on one side of the center of rotation 75 and a clearance space on the other side, a lever provided for each of the said inlet and exhaust miter valves and resting with one end on the corresponding cam surface of the weigh bar, an adjustable support for 80 the other end of said levers, a spindle resting on each of the levers and adapted to operate the corresponding valve, and means to couple the hydraulic valve to the hydraulic cylinder, all as and for the purpose set forth 85 and shown.

2. In operating gear for hydraulic valves, the combination, with valve mechanism comprising an inlet and an exhaust miter valve connected with each other, of a weigh bar 90 placed at a distance from the center line of the valves and having differential cam surfaces on one side of the center of rotation and a clearance space on the other side, means to rock said weigh bar, a lever provided for each of the said valves one end of the lever resting on the corresponding cam surface of the weigh bar, an adjustable support for the other end of the levers, a spindle resting on each of the levers and adapted 100 to operate the corresponding valve, and means for coupling the hydraulic valve to a cylinder, all substantially as and for the purpose set forth and shown.

In testimony whereof I have hereunto set 105 my hand in the presence of two subscribing witnesses.

HENRY CROWE.
